UNITED STATES PATENT OFFICE.

RALPH L. MORGAN, OF WORCESTER, MASSACHUSETTS, ASSIGNOR OF ONE-HALF TO THE MORGAN CONSTRUCTION COMPANY, OF WORCESTER, MASSACHUSETTS, A CORPORATION OF MASSACHUSETTS.

GAS-PRODUCER.

SPECIFICATION forming part of Letters Patent No. 686,629, dated November 12, 1901.

Application filed September 20, 1899. Serial No. 731,045. (No model.)

To all whom it may concern:

Be it known that I, RALPH L. MORGAN, a citizen of the United States, residing at Worcester, in the county of Worcester and 5 Commonwealth of Massachusetts, have invented new and useful Improvements in Gas- Producers, of which the following is a specification, accompanied by drawings forming a part of the same, in which—

10 Figure 1 represents a plan view of a gas- producer embodying my invention, the combustion-chamber being shown in horizontal sectional view. Fig. 2 is a central vertical sectional view of so much of the gas-pro- 15 ducer as is necessary to illustrate the nature and character of my invention. Fig. 3 is a sectional view of one of the scraper-arms on line 3 3, Fig. 2. Fig. 4 represents a top view of two gas-producers placed in line with an 20 ash pit or trench below the floor and an endless-chain scraper and conveyer by which the ashes collected in the trenches are con- 25 veyed to a receptacle. Fig. 5 is a front elevation of a gas-producer with the floor con- taining the ash-pit shown in sectional view 30 on line 5 5, Fig. 4. Fig. 6 is a side view of the two gas-producers shown in Fig. 4, with the floor shown in sectional view on the line of one of the ash-conveyers.

35 Similar letters refer to similar parts in the different figures.

The objects of my invention are to provide improved means for discharging the ash and non-combustible material from the producer; 35 to provide means for the agitation of the fuel in order to prevent the formation of ducts or air-passages; to provide means for moistening the ashes before their delivery; to provide a simple construction of the ash- 40 receptacle and ash-delivering mechanism which will allow convenient access to the ash-chamber; to provide means whereby the ashes or other non-combustible material are delivered entirely outside the combustion- 45 chamber and ash-receptacle, and to further provide means for gathering the ashes dis- charged from the gas-producer into a pit or trench and for conveying the collected ashes 50 discharged from several producers placed in a line into a common receptacle, and these

objects are attained by means of the construction and arrangement of parts, as hereinafter described, and set forth in the annexed claims.

Referring to the drawings, A denotes the 55 combustion-chamber; B, the ash-hopper, constructed in the present instance of cast iron and provided at its upper edge with a flange B', on which a masonry wall A' is supported, inclosing the combustion-chamber A. 60 The ash-hopper is provided at its lower edge with a series of pointed teeth B², forming a serrated edge, and it is supported upon feet B³, which rest upon the bottom of an ash-pan C. The ash-pan C forms the bottom of 65 the combustion-chamber and is provided at its center with the hub C', extending upwardly into the ash-hopper B, and also with a downwardly-extending hub C², said hub forming a bearing for a hollow shaft. 70

The bottom of the ash-pan C rests upon a floor of masonry and is provided with upturned edges C³, extending a short distance above the lower serrated edge of the ash-hopper, and between the serrated edge of the 75 ash-hopper and the bottom of the ash-pan C is an open space D, through which the ashes are forced from the ash-hopper into the annular space C⁴ between the upturned edge C³ and the outside of the ash-hopper B. Journaled in the hubs C' and C² is a hollow shaft E, rotated by driving mechanism consisting in the present instance of a worm-gear E', engaged by a worm E², carried by a shaft E³, and driven by the cones E⁴ E^{4a}. The shaft E 80 is provided with a central hole E⁵, which extends throughout its length, and attached to the upper end of the shaft E are scraper-arms F F, which project from the upper end of the shaft E with a slight downward curve 90 toward the bottom of the ash-pan C. The front and rear edges F' F² of the scraper-arms are also slightly curved, as shown in plan view in Fig. 1, and the arms rotate in the direction of the arrows 1 1, Fig. 1. The 95 scraper-arms F are thicker at their rear edges F² than at their front edges F', as shown in sectional view in Fig. 3, in which the direction of the movement of the scraper-arms is indicated by the arrow 4. The driving mech- 100

- anism of the shaft E is located in a pit G, to which air is supplied through a conduit H and a jet of steam is introduced by a steam-pipe I.
- 5 The upper end of the hollow shaft E is covered by a hood F³, raised above the upper end of the shaft, to allow the current of air and steam to pass into the combustion-chamber, and a depending annular flange F⁴, carried by the upper end of the shaft E, overlaps the upper end of the hub C'. In the operation of the gas-producer the mass of fuel contained in the combustion-chamber A rests upon the bed of ashes contained in the ash-hopper B and supported upon the bottom of the ash-pan C, and the ash-pan C is supplied with water, as indicated by the broken line J. A slow rotary motion is imparted to the scraping-arms F F, which causes the lower 15 stratum of ashes submerged in water contained in the pan C to be forced outwardly through the open spaces D between the bottom of the ash-pan and the serrated edge of the ash-hopper in the direction of the arrows 20 2 2, Fig. 2, and into the annular space C⁴. As the annular space C⁴ becomes filled with ashes they are crowded upwardly over the upturned edge C³ in the direction of the arrows 3 3, Fig. 2, of the ash-pan and allowed 25 to fall by gravity upon the floor K, from which they are removed by the attendant, or they may be allowed to fall into pits and removed by a mechanical conveyer, as shown in Figs. 4, 5, and 6. Clinkers and similar non-com- 30 bustible material are crowded by the scraper-arms F beneath the fixed teeth B² of the serrated edge, by which they are ground or disintegrated, so that they may be pushed with the ashes into the annular space C⁴.
- 35 40 Only the tips of the scraper-arms F approach the bottom of the pan C, the main body of the arms being curved upwardly to their point of connection with the rotating spindle E, so that they extend through the mass of ashes 45 into the body of fuel contained in the combustion-chamber, and as they rotate the fuel contained in the combustion-chamber becomes gently agitated. The agitation of the fuel by the rotation of the scraper-arms 50 causes it to lie in a mass of uniform thickness upon the bed of ashes in the ash-hopper and prevents the formation of air ducts or passages through the mass of fuel which is likely to occur when the fuel remains in a 55 state of rest. The formation of ducts or passages through the fuel allows the blast of steam and air admitted through the hollow shaft E to pass upwardly through the fuel, producing an uneven combustion and forming 60 clinkers.

The agitation of the fuel is not only caused by the elevation of the central section of the scraper-arms, but it is also increased by making the scraper-arms thicker at their rear edges F² than at their front edges F', so that as the inclined upper surface F⁵ of the scraper-arms pass beneath the fuel a slight

lifting and falling motion may be imparted to the fuel which is raised while in contact with the surface F⁵ and falls when it reaches 70 the rear edge F².

The upturned edges C³ of the ash-pan extend a short distance above the serrated edge B² of the ash-hopper and also some distance above the level of the floor K, so that as soon 75 as the annular space C⁴ becomes full of ashes the overflow from the ash-pan is carried downwardly by gravity upon the floor entirely outside of the ash-pan.

The space D allows access to the ash-hopper from the annular space C⁴ of the ash-pan, and the flange F⁴ protects the bearing of the hollow shaft from ashes.

In Figs. 4, 5, and 6 I have shown an arrangement of two gas-producers L L, placed 85 in line with parallel ash pits or trenches L' L' on each side of the gas-producers. Between the ash-pits L' L' and between the gas-producers the floor is inclined in opposite directions, as shown at L² L². The two inclined 90 surfaces L² L² meet at an apex L³ on the central line of the gas-producers, so that the ashes discharged over the side walls C³ of the ash-pans will be conveyed by the inclined floor-surfaces L² L² into the two parallel ash 95 pits or trenches at each side of the gas-producers. Running in the ash pits or trenches L' L' are endless-chain conveyers M M, carrying 100 scrapers N N, by which the ashes are scraped along the bottom of the ash pits or trenches 105 in the direction of the arrow 5, Fig. 6, and conveyed through an elevated trough O to a spout P, through which they are conveyed to a car Q. The endless conveyer-chains M M are suitably supported throughout their 110 length by rolls R R and are driven by the sprocket-wheels S S, attached to a revolving shaft T. The discharge and removal of ashes from the gas-producers is thereby rendered entirely automatic.

What I claim as my invention, and desire to secure by Letters Patent, is—

1. In a gas-producer, the combination with a combustion-chamber, of a pan having a bottom forming the bottom of said combustion-chamber and extending radially beyond the walls of the chamber, masonry walls supporting the outer edge of said pan and inclosing a pit beneath the center of the pan, a hub extending upwardly from the center of said pan forming a bearing for a rotating shaft, a rotating shaft journaled in said bearing and scraper-arms carried by said shaft, substantially as described.

2. In a gas-producer, the combination of a 125 combustion-chamber, a pan having a bottom forming the bottom of said combustion-chamber and having raised sides and provided with a bearing in its center for a rotating shaft, a rotating shaft and scraper-arms carried by said shaft and rotating in the plane 130 of the raised sides of the pan, substantially as described.

3. In a gas-producer, the combination of a

- combustion-chamber having a bottom provided with a bearing for a vertical rotating shaft, a vertical rotating shaft and scraper-arms attached to said shaft at some distance above the bottom of the combustion-chamber, said arms extending outwardly and downwardly toward the bottom of said chamber, substantially as described. 5
4. In a gas-producer, the combination of a combustion-chamber having a bottom provided with a bearing for a vertical rotating shaft, a vertical rotating shaft, scraper-arms attached to the upper end of said shaft and at a distance above the bottom of the combustion-chamber, said arms extending radially outward and being curved downward toward the bottom of the combustion-chamber, and means for rotating said arms, substantially as described. 10
5. In a gas-producer, the combination of a combustion-chamber, a pan having a bottom forming the bottom of said combustion-chamber and having raised sides extending above and outside the lower edge of said combustion-chamber and with a bearing in its center for a rotating shaft, a rotating shaft and scraper-arms carried by said shaft and rotating in the plane of the raised sides of the pan, substantially as described. 15
6. In a gas-producer, the combination of a combustion-chamber, a rotating shaft, scraper-arms carried by said shaft having their upper surfaces inclined to the plane of rotation of said arms, substantially as described. 20
7. In a gas-producer, the combination of a combustion-chamber, an ash-hopper having vertical walls flush with the walls of the combustion-chamber and provided with teeth on their lower edge, a bottom extending radially beyond the walls of said ash-hopper and having a space between said bottom and the serrated edge of the ash-hopper, raised sides at the outer edge of said bottom forming a pan, 25
- and a rotating shaft journaled in a bearing in said bottom and scraper-arms carried by said shaft and rotating in the plane of the raised sides of the pan, whereby the ashes are pushed radially outward beyond the walls of the ash-hopper, substantially as described. 30
8. In a gas-producer, the combination with an ash-hopper, of a bottom extending radially outward beyond the walls of the hopper with a space between the bottom and the lower edge of the hopper, said bottom having raised sides forming a pan, a rotating shaft journaled in said bottom, scraper-arms carried by said shaft and rotating in the plane of the raised sides of the pan, and a trench or pit below the bottom of said pan into which the ashes are delivered by gravity, substantially as described. 35
9. In a gas-producer, the combination with the ash-hopper provided with a bottom, of scraper-arms for forcing the ashes off said bottom, an ash pit, or trench, below the edge of said bottom, scrapers for removing the ashes from said pits or trenches, and means for moving the scrapers lengthwise said pits or trenches, substantially as described. 40
10. In a gas-producer, the combination with the ash-hopper provided with a bottom, of an ash pit, or trench, inclined surfaces beneath the edge of said bottom, whereby the ashes delivered by the producers are conducted to said ash-pit, and means for forcing the ashes radially from said bottom upon said inclined surfaces, substantially as described. 45

In testimony whereof I have signed my name to this specification, in presence of two subscribing witnesses, on this the 14th day of September, 1899.

RALPH L. MORGAN.
